UNITED STATES PATENT OFFICE.

EDWARD W. NIMMER, OF MILWAUKEE, WISCONSIN.

COMBINATION MEDICINE-SPOON.

1,277,635.

Specification of Letters Patent. Patented Sept. 3, 1918.

Application filed June 7, 1916. Serial No. 102,257.

To all whom it may concern:

Be it known that I, EDWARD W. NIMMER, a citizen of the United States, residing at Milwaukee, in the county of Milwaukee, State of Wisconsin, have invented certain new and useful Improvements in Combination Medicine-Spoons; and I do hereby declare the following to be a full, clear, and exact description of the invention, such as will enable others skilled in the art to which it appertains to make and use the same.

This invention relates to combination medicine spoons.

One important object of the invention is to provide a spoon in the use of which a patient will be positively prevented from closing his mouth after the point of the spoon has been inserted therein, so that the contents of the spoon will not be spilled over the patient's face.

Another important object of the invention is to provide an improved form of spoon wherein medicines injurious to the teeth may be administered without coming in contact with the teeth, the medicines being delivered far back in the mouth.

A third important object of the invention is to provide an improved spoon of this description having the removable 30 cover and provided with an extended tongue depressor projecting beyond the cover so that the patient can not close the end of the spoon with the tongue.

A fourth important object of the invention is to provide means for observing the interior of the mouth, said means being carried by the spoon.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is a plan view of a spoon constructed in accordance with this invention; Fig. 2 is a side elevation thereof;

Fig. 3 is a longitudinal median section through such a spoon;

Fig. 4 is a section on the line 4—4 of Fig. 1.

In carrying out the objects of this invention there is provided a spoon having a bowl 10 on the interior of which are provided graduations 11 so that the number of drops in a dose may be regulated. The spoon has at one end a handle having a parallel sided portion 12 and a terminal portion 13, the latter being bent downward. At the other end or point of the spoon is also provided a second parallel sided portion 14, the central portion of which is bent to form a longitudinal groove 15 which is depressed adjacent the body of the spoon and terminates forwardly in a very shallow groove. Slidably mounted on the edges of the portion 14 is a cover plate 16 which is transversely 70 arcuate and is provided with edges 17 bent under the edges of the portion 14. By this means the cover plate may be readily slipped onto or removed from the portion 14, the device being thus rendered easily cleanable 75 when separated.

Extending forwardly from the portion 14 and being reduced in width therefrom is a terminal finger portion 18 which is downwardly bent and is provided with an under 80 surface having corrugations or other roughening means formed thereon. It is to be noted that this downwardly bent portion projects beyond the cover plate also.

Mounted on the parallel sided portion of the handle is a slide 19 which carries a magnifying glass 20 having its focal axis in alignment with the center of the space between the cover plate and portion 14 of the spoon.

In administering a dose of medicine, the medicine is poured out into the body of the spoon, to the proper height, this being regulated by the graduations 11. When the medicine has been poured into the spoon, the 95 forward end is inserted in the patient's mouth and the finger portion 18 pressed down upon the tongue, as far back as can be conveniently done without causing the patient to gag. It will be seen that when in 100

this position the forward end of the groove will be well within the patient's mouth so that when the handle of the spoon is tilted upward, the contents will run out to the 5 back of the mouth and will not strike the teeth. Moreover, the patient's lips will naturally close down, especially if a young child, but cannot close off the passage since the cover plate 16 protects the groove. Furthermore, the tongue, being held down, cannot be used to close the end of the passage between the cover plate and portion 14.

It is to be observed that the glass 20 is adjustable on the handle so that it may be 15 brought into proper focus to observe the interior of the patient's mouth through the opening between the cover plate and portion 14, or for this purpose, the cover plate may be removed.

20 It will of course be apparent to those skilled in the art that in the use of the present spoon, the concaved mirror with central opening such as commonly is used by nose, throat and eye specialists, is employed 25 to reflect light emanating from a source over the patient's head as is the common practice when examining the throat, the nostrils, or eyes of a patient.

It will be further noted that the extension 30 18 beyond the cover plate 16 prevents the spasmodic rising of the patient's tongue across the line of vision which would naturally occur if the portion 14 were pressed down upon the tongue and there were no extension 18 beyond the cover plate.

It will also be observed that after the medicine has been given and the spoon withdrawn, it may be readily taken apart for cleaning.

40 There has thus been provided a simple and efficient device of the kind described and for the purpose specified.

It is obvious that many minor changes may be made in the form and construction 45 of the invention without departing from the material principles thereof. It is not therefore desired to confine the invention to the exact form herein shown and described but it is wished to include all such as properly 50 come within the scope claimed.

It will be obvious that not only may the spoon be used for administering medicine under usual conditions, but also it may be used with the spoon and magnifying glass 55 in combination, the spoon with its cover serving to hold the lips of the patient parted while an inspection of the throat is made through the magnifying glass and through the passage between the spoon bowl and

60 cover. Also when it is desired to administer medicine to a particular affected spot at the back of the throat, not discernible with the naked eye, the spoon may be directed to this particular spot by looking

through the magnifying glass and through 65 the passage between the spoon bowl and the cover at the time the medicine is being administered.

Having thus described the invention, what is claimed as new is:—

70 1. A medicine administering spoon comprising a bowl having a tubular extension from its point, the axis of which extension is straight and positioned above the top of the bowl, a handle at the opposite side of 75 the bowl from the tubular extension and a magnifying glass slidably mounted upon the handle in axial alinement with the tubular extension and movable toward and away from the tubular extension for focusing 80 whereby light may pass through the tubular extension with the medicine to the part of the throat of a patient to be directly treated and such part may be viewed through the magnifying glass.

85 2. A medicine administering spoon comprising a bowl having a tubular extension from its point, the axis of which extension is straight and positioned above the top of the bowl, a finger extending forwardly and downwardly from the lower side of the tubular extension to prevent rising of the tongue of the patient across the opening of the tubular extension, a handle at the opposite side of the bowl from the tubular extension and a magnifying glass mounted upon the handle in axial alinement with the tubular extension and movable toward and away 90 from the tubular extension for focusing 95 whereby light may pass through the tubular extension with the medicine to the part of the throat of a patient to be directly treated and such part may be viewed through the magnifying glass.

100 3. A medicine administering spoon comprising a bowl provided with a tubular extension projecting forwardly from the point of said bowl, the axis of which extension is straight and positioned above the top of the bowl, and a finger extending forwardly and downwardly from the lower edge of the end of the tubular extension to prevent rising 105 of the tongue of the patient across the opening of the tubular extension.

110 4. An article of the class described comprising a straight tubular portion, a handle connected with one end of the tubular portion and below the longitudinal axis of the latter, a magnifying glass slidably mounted upon the handle in axial alinement with the 115 tubular portion and movable toward and away from the tubular portion for focusing, the tubular portion being adapted to direct a remedy therethrough to a point viewed 120 through the magnifying glass.

125 5. A device of the class described comprising a tubular member having a handle connected with one end thereof and posi-

tioned below the longitudinal axis of the tubular portion, a finger extending longitudinally and downwardly from the lower side of the opposite end of the tubular portion to prevent rising of the tongue of the patient across the opening of the tubular portion and a magnifying glass slidably mounted upon the handle in axial alinement

with the tubular portion and movable toward and away from the latter. 10

In testimony whereof I affix my signature in the presence of two witnesses.

EDWARD W. NIMMER.
